C. HAUSMANN.
SCALE,
APPLICATION FILED MAR. 31, 1921.

1,428,165.

Patented Sept. 5, 1922.

UNITED STATES PATENT OFFICE.

CHARLES HAUSMANN, OF JERSEY CITY, NEW JERSEY, ASSIGNOR TO HERMAN KOHLBUSCH, SR., INC., OF JERSEY CITY, NEW JERSEY, A CORPORATION OF NEW JERSEY.

SCALES.

Application filed March 31, 1921. Serial No. 457,496.

To all whom it may concern:

Be it known that I, CHARLES HAUSMANN, a citizen of the United States, and a resident of Jersey City, in the county of Hudson and 5 State of New Jersey, have made and invented certain new and useful Improvements in Scales, of which the following is a specification.

My invention relates to a scales and particularly to that type known as a balance.

The object of my invention is to provide a scales which will be neat and attractive in appearance, simple and efficient in operation, may be economically manufactured, and at 15 the same time an instrument of precision such as may be used for comparatively fine weighings such as used for the determination of the size of diamonds.

A further object is to provide a scales 20 which is of the balance type, is readily portable to the extent of being housed within a box or casing which may be carried in the pocket.

A further object is to provide a scales of 25 the aforementioned character having improved means for raising and maintaining in a raised position, the fulcrum and the beam, the mechanism whereby this is carried out being simple in construction and particularly convenient and accessible for its 30 operation.

With the foregoing and other objects in view, my invention consists in the improved scales illustrated in the accompanying drawing and hereinafter described and claimed, and in such variations and modifications 35 thereof as will be obvious to those skilled in the art to which my invention relates.

In the drawing accompanying and forming 40 a part of this specification and wherein the preferred embodiment of my invention is illustrated:

Figure 1 is a view in front elevation of 45 my improved scales;

Figure 2 is a view in section taken on the line 2—2 of Figure 1;

Figure 3 is an enlarged detail view in section of the raising lever, the fulcrum and fulcrum support being in lowered position, 50 allowing the scales pans to rest upon a supporting surface, and

Figure 4 is a similar view with the raising lever depressed and the fulcrum and scales beam raised, allowing the scales beam to

freely swing and the desired weight measurements to be made. 55

Referring specifically to the several views wherein similar reference numerals designate corresponding parts throughout, a box or casing 10 is provided with the hinged lid 11 and a strut 12 which is hingedly secured to the box and engages the lid and is adapted to hold it in an upright position. Securely attached to the lid and preferably located upon the center line of the inner face thereof, is the base plate 13 which terminates at its lower extremity in the outwardly extending bracket 14. The bracket is provided with the downwardly extending and offset arm 15. 60

Slidably mounted upon the base plate is the fulcrum support 16 which is provided with the slot 17 therein through which extends the retaining screw 18, thus limiting the sliding movement of the fulcrum support and holding it in position against the base plate. The lower extremity of the fulcrum support is cylindrical in cross section as at 19 and extends through a suitable opening 20 formed in the outstanding 65 bracket of the base plate. The fulcrum support carries the fulcrum 21 at its upper extremity, which in turn supports the scales beam 22 in the usual manner. Suitable pans 23 are secured to the scales beam and 70 the various connections preferably carried out by suitable knife blades, as is customary in instruments of this character. 75

Mounted upon the fulcrum support rod is the dial 24, over which travels the indicator 25 which is secured to the scales beam. The indicator 25 extends through an opening 26 in the fulcrum, which is sufficiently large 80 so as to allow the indicator to swing freely and thus indicate the extent of oscillation 85 of the scales beam. The cords by means of which the pans are suspended are of such length that when the fulcrum support is in its lowered position and resting upon the shank of the retaining screw 18, the pans 90 will rest upon the supporting surface upon which the casing 10 is located. 95

In order to raise the scales beam and maintain it in its raised position, I have provided the outstanding bracket and downwardly projecting arm 15 with the slot 27 and between the walls of which is pivoted 100 the raising lever 28. The outer and pro-

truding extremity of the lever is provided with the thumb-engageable knob or projection 29, while the inner extremity is provided with the cam raising face 30 and with 5 the offset locking end 31. The raising face 30 extends so that the normal thereto will approximately include the fulcrum support 19, while the offset locking end 31 is provided with the face 32 having the normal there- 10 to extending approximately through or above the pivotal mounting of the raising lever. The pivotal mounting of the raising lever is located so that when the fulcrum support and the scales beam are in their 15 lowered position the raising lever will extend substantially perpendicular to the fulcrum support. As the outer extremity of the raising lever is depressed, the fulcrum support is raised, the end of the rod 19 trav- 20 eling along the cam face 30 and being raised therewith until the offset end 31 is reached, whereupon the further depression of the raising lever brings the cam face 30 to a stop against the lower surface 33 of the 25 bracket and allows the extreme end of the rod 19 to pass a slight distance down the locking end 31. The downward force ex- 30 ereted by the fulcrum support will then pass through or above the pivotal mounting of the raising lever and which, in connection with the slight jamming action whereby the rod 19 is moved against the base plate, causes a self-locking action to take place and the fulcrum support and fulcrum to remain in 35 an elevated position until such time as it is again desired to lower them, whereupon the outer extremity of the raising lever is raised, releasing the rod 19 from the offset end and allowing it to again travel down 40 the cam face 30 as the raising lever is re- turned to its normal position, whereby the fulcrum support is lowered and again rests upon the retaining screw 18 and the scale pans upon the supporting surface.

45 The housing 10 is adapted to receive the scales beam and pans therein, so that the entire apparatus is adapted to nest within the housing 10. A suitable catch 34 is provided whereby, after the strut 12 has been 50 unfastened from the lid and the lid moved into its lowered position, the latch will lock and hold the lid in a closed position.

My improved scales as thus constructed embodies a minimum amount of raw ma- 55 terial, may be economically manufactured, will be durable and efficient in service, as well as precise in its weight measurements, and particularly convenient to operate, due to the readily accessible fulcrum raising 60 lever and its ability to maintain the scales beam in its raised position.

Having thus described and explained my invention, I claim and desire to secure by Letters Patent:

65 1. A scales of the character described

comprising a base plate, a bracket having an aperture extending therethrough, a fulcrum support rod having a slot therein and extending through the aperture in said bracket, a retaining member carried by said 70 base plate and passing through the slot in said fulcrum support, holding the same in position and limiting the movement thereof, a raising lever pivotally carried by said bracket and adapted to engage the protrud- 75 ing end of said fulcrum support and raise and lower the same, and a scales beam and pans carried by said fulcrum support.

2. A scales comprising a support, a base 80 plate carried thereby, a bracket with an aperture extending therethrough and having a depending arm, a fulcrum support rod extending through the aperture in said bracket and provided with a slot adjacent its upper extremity, a retaining member ex- 85 tending through said slot carried by said base plate and slidably securing said support to said base plate and limiting the sliding movement thereof, a raising lever pivotally secured to 90 said depending arm of the bracket engaging said fulcrum support rod and adapted to raise and lower the same and lock said fulcrum support rod in an elevat- 95 ed position, a fulcrum carried by said ful- 100 crum support, and a scales beam and associated parts adapted to engage said fulcrum.

3. An apparatus of the class described consisting in part of a fulcrum supporting rod, a member slidably mounting the same 100 and having a bracket receiving said rod therethrough, and a raising lever pivotally secured to said bracket, having a face adapted to engage and raise said supporting rod and further provided with an offset locking 105 end adapted to lock said fulcrum supporting rod in an elevated position.

4. A portable scales comprising a base plate, a bracket, a fulcrum support rod, means associated with said base plate for 110 slidably mounting said fulcrum support rod and limiting the sliding movement thereof, a raising lever having an offset end pivotally secured to said bracket, en- 115 gaging the lower extremity of said fulcrum support rod and adapted to raise and lower the same and to maintain the fulcrum sup- port rod located in an elevated position, a fulcrum carried by said fulcrum support rod, and a scales beam and associated parts 120 adapted to engage and be supported by said fulcrum and be operative when said fulcrum support rod is in an elevated position and to be inoperative and held against oscillation when said fulcrum support rod 125 is in a lowered position.

5. A portable scales comprising a box having a hinged lid and means for main- 130 taining the same in an upright position, a base plate carried by the inner wall of said

lid, a bracket, a fulcrum support rod, means associated with said base plate for slidably mounting said fulcrum support rod and limiting the sliding movement thereof, a 5 raising lever having an offset end and pivotally secured to said bracket, engaging the lower extremity of said fulcrum support rod and adapted to raise and lower the same and to maintain the fulcrum support rod 10 locked in an elevated position, a fulcrum carried by said fulcrum support rod and a scales beam and associated parts adapted to engage and be supported by said fulcrum and be operative when said fulcrum support 15 rod is in an elevated position and to be inoperative and held against oscillation when said fulcrum support rod is in a lowered position.

6. A portable scales comprising a box 20 having a hinged lid and means for maintaining the same in an upright position, a base plate carried by the inner wall of said lid, a bracket, a fulcrum support rod, means associated with said base plate for slidably 25 mounting said fulcrum support rod and

limiting the sliding movement thereof, a raising lever having an offset end and pivotally secured to said bracket, engaging the lower extremity of said fulcrum support rod and adapted to raise and lower the same 30 and to maintain the fulcrum support rod locked in an elevated position, a fulcrum carried by said fulcrum support rod, and a scales beam and associated parts adapted to engage and be supported by said fulcrum 35 and be operative when said fulcrum support rod is in an elevated position and to be inoperative and held against oscillation when said fulcrum support rod is in a lowered position, said box provided with a 40 compartment therein adapted to receive and nest the scales beam and associated parts therein.

Signed at Jersey City in the county of Hudson and State of New Jersey this 24th 45 day of March A. D. 1921.

CHARLES HAUSMANN.
